UNITED STATES PATENT OFFICE.

EDWIN R. FELLOWS, OF SPRINGFIELD, VERMONT, ASSIGNEE TO THE FELLOWS GEAR SHAPER COMPANY, OF SPRINGFIELD, VERMONT, A CORPORATION OF VERMONT.

MEANS FOR GENERATING AND CUTTING IRREGULAR GEARS.

1,190,391.

Specification of Letters Patent. Patented July 11, 1916.

Application filed April 22, 1915. Serial No. 23,262.

To all whom it may concern:

Be it known that I, EDWIN R. FELLOWS, a citizen of the United States, and resident of Springfield, in the county of Windsor and State of Vermont, have invented certain new and useful Improvements in Means for Generating and Cutting Irregular Gears, of which the following is a specification.

The present invention relates to the art of generating and cutting teeth on irregular gears, by which I mean gears having teeth arranged on a pitch line which is otherwise than concentric with the axis about which either the gear is designed to rotate or a pinion meshing with the gear is designed to revolve.

In my application for patent, Serial Number 858,192 filed August 22, 1914, I have illustrated a means for generating and cutting the teeth of such a gear wherein the gear is held by a floating holder and is given a movement, relatively to a tooth-generating cutter during the generating and cutting operation, which is similar to the relative movement between the gear and the pinion with which it is designed to mesh.

The apparatus and means which form the subject of the present invention are of the same general nature as those shown in my application aforesaid, but possess modifications and refinements having for their object to accomplish the desired end with less mechanical resistance and with possibly greater accuracy.

Briefly stated the principal object of the present invention is to provide a means for so moving an irregular gear blank translatably and revolvably, in connection with generating motion of a gear-shaped planing cutter, or other cutter capable of cutting gear teeth of the desired form, during the cutting operation as to produce exactly the same relative movements between the blank and the cutter in directions transverse to the axis of the blank, as take place between the gear and the standard pinion with which it is designed to run in mesh, and to effect this movement in a positive manner and with the minimum of frictional or other resistance.

The particular gears of which the teeth are to be generated and cut by the present apparatus include an internal irregular gear of four equal and symmetrically ar-

ranged lobes, and an external gear of generally elliptical shape and of smaller area than the space surrounded by the teeth of the internal gear; which is placed in such space, and meshes with a number of floating pinions, which latter also mesh with the internal gear and are adapted to have a planetary motion when either the external gear or the internal gear is rotated relatively to the other.

One form of the means which I have adopted and desire to protect in the present application for giving the desired movements to the gear blank consists of a set of master gears and pinions, to one of which master gears the blank is connected, and of which one of the pinions is used as the driver for giving the generating movement to the gear being cut, in connection with a cutter which may be of any sort capable of generating the forms of gear teeth at the same time that it cuts them, by a combination of relative movements between the cutter and the work piece. One form of such cutter, here illustrated, has peripheral projections shaped similarly to the teeth of a spur gear and arranged on a pitch line approximately equal in diameter to the pitch line of such driving pinion. Other forms of means for the same purpose herein illustrated comprise co-acting elements connected with the master gear and the table on which the work holder is supported for positively shifting the work holder when receding portions of the pitch line of the master gear approach the driving pinion. Essentially the same means, with minor variations adapted to the particular work in hand, may be provided and arranged for cutting any shape or character of internal or external irregular gear, wherefore the particular description which follows of the embodiment of such means adapted to a particular purpose is not to be taken as limiting the present invention to the particular mechanism described, or otherwise, except in accordance with the appended claims.

In the drawings, Figure 1 is a vertical mid section of an apparatus embodying the principles of my invention arranged for cutting an internal gear. Fig. 2 is a similar view showing the apparatus arranged for cutting an external gear. Fig. 3 is a sectional plan view of the work holder taken

on line 3-3 of Fig. 1. Fig. 4 is a similar view showing a modification. Fig. 5 is a sectional view of another form of apparatus embodying the same principles designed for cutting an external gear. Fig. 6 is a plan view of the parts below the line 6-6 of Fig. 5. Fig. 7 is a sectional view showing the principles of the last two figures applied for cutting an internal gear. Fig. 8 is a plan view of parts below the line 8-8 of Fig. 7.

The same reference characters indicate the same parts in all the figures.

Referring to Figs. 1 to 3 of the drawings, 10 represents a fixed table mounted on the base of a gear cutting machine and having a flat and smooth upper work-supporting surface. It is mounted on a quill 11 secured in the work supporting part of a gear cutting 20 machine, such as, for example, the carrier shown in my prior Patent No. 676,227. A spindle 12 is mounted rotatably in the quill and contains an arbor 13. Said spindle may be considered as the driving spindle for imparting generating movements to the work. 14 represents a cutter which is made so as to generate and cut gear teeth by a combination of axial cutting movements with rotatory generating movements. This cutter 30 has projections 15 similar in outline, and equal in pitch to the teeth of a standard pinion or gear and arranged on a circular pitch line, but differing from the teeth of the ordinary gear in that the edges of the 35 teeth at the end face of the cutter are made as cutting edges and the faces at the sides and extremities of the teeth and at the bottom of the spaces between the teeth are backed off or inclined toward the axis of the 40 cutter to give clearance in the cutting operation. This cutter is mounted on a spindle 16 by which is given the necessary reciprocating cutting movements and rotatory generating movements. Without limiting the 45 present invention to any particular organized machine, I may say that I have applied the same to a machine of the type illustrated in my Patents No. 579,708 of March 30, 1897; No. 676,227 of June 11, 1901; and No. 50 1,028,343 of June 4, 1912, and that in practice I have rotated the spindle 12 and have rotated and reciprocated the spindle 16 by mechanisms essentially the same as the mechanisms employed for rotating the work holding spindle and for reciprocating and rotating the cutter spindle shown in the said patent.

The gear blank on which the teeth are being cut in the arrangement shown in Fig. 60 1 is designated 17 and it is mounted upon a floating work holder 18 which rests upon the table 10 and is free to move in any manner in any direction over the surface of such table, except that it is restrained from rotating 65 completely about the axis of spindle 12

by a stop 10^a of any suitable character, which is fixed to the table 10 in position to bear against the edge of the holder 18. The gear blank is grasped at its periphery by chuck jaws 19 of the floating holder.

In the under side of the holder is a recess wherein there is placed, and held against rotation by a bolt 21 and a dowel pin 22, a combined former and master gear 23, having an internal line of teeth 24 arranged on a pitch line of the same outline as the pitch line of the teeth to be cut in the gear blank 17. The part which constitutes the former is an internal rib 25 of which the outline corresponds with the pitch line of the teeth 24. In the illustrated embodiment of Figs. 1 and 3 the surface of the rib 25 conforms exactly in outline, curvature, and irregularity to the pitch line of the teeth 24 and is in effect a continuation of the pitch surface 25 of such teeth, but this condition may be altered, as I will presently show. Reference to Fig. 3 will show the shape of the former 25 and master gear 23. From this view it will be clearly apparent that the line of the teeth is irregular in the sense of not being on a circle concentric with the geometric axis 26^b of the master gear, although the line of the teeth forms a symmetrical geometric figure. This gear has four equal and symmetrical lobes, the approximate centers of curvature of which are not in the geometric axis of the gear.

Fixed upon the arbor 13 is a combined driving pinion and former 26, the pinion 100 having teeth 27 meshing with the teeth of the master gear and that part of it which constitutes the former having a peripheral surface 28 conforming to the pitch surface of the teeth and being in effect the prolongation of such pitch surface. This pinion is the driving pinion of the work holder; it is keyed to the arbor 13 and is clamped thereon by a nut 29. The pitch diameter of the pinion 26 is approximately equal to the pitch diameter of the teeth 15 of cutter 14, and the axis of the pinion is approximately in line with the axis of the cutter, that is, after the cutter has been fed the required depth into the work. It is, of course to be understood that the machine to which this apparatus is applied has a depth feed for the preliminary step of feeding either the cutter relatively to the work, or the work 110 relatively to the cutter, to the proper depth 115 for forming the teeth, and that the present drawings illustrate the condition after the depth feed has been completed. It is after the cutter has been caused to cut to the required depth into the tooth bearing portion 120 of the work that the condition illustrated and above described obtains. In this condition the point in the pitch line of the cutter 125 which comes tangent to the pitch line of the gear blank is in exact alinement with the 130

point of tangency between the pitch lines of the master gear and the master pinion.

The combined pinion and former 26 is one of a number of similar combined pinions and formers 30, 31, 32, 33 and 34, which are arranged at intervals about the periphery of the master gear and are identical as to diameter and pitch with the driving pinion. In the space surrounded by the said pinions is placed an irregular external gear 35 having teeth 36, with which is associated a cam or former 37. The surface of the former 37 has the same outline as the pitch line of the teeth 36 and conforms exactly with this pitch line, each axial element of the former surface being in line with a corresponding point of the pitch line of the teeth. In other words, the pitch line of the teeth and the surface of the former are in effect parts of the same geometrical surface, and the relation between the former surface and pitch line of this gear is the same as that already described between the former surface and pitch line of the master internal gear and of the driving pinion 26, and that of the other pinions. The pinions 26, 30, 31, 32, 33 and 34 are so arranged about the common axis 26^b of the irregular gears 23 and 35 that the centers of the pinions on opposite sides of the gear 35 are in lines passing through the point 26^b, which is the common axis of revolution of the entire collection of gears and pinions; and the outline of the combined external gear and former 36 is so designed relatively to the pitch outline of the internal gear and former 23 that in all positions of revolution of the external gear about this axis, the same condition will hold and each of the pinions will be in mesh with both the internal and external gears, and their former surfaces will remain in tangent contact with the peripheral surface of the external former 37 and the surface of the internal former 25.

All of the elements described, except the pinion 26, are floating, that is free to shift upon the table 20 and are confined only by the intermeshing of their teeth and the tangent contact of their formers with one another, and by the restraint from complete rotation of the entire collection imposed by the stop or abutment 10^a. Thus when the driving pinion is rotated the master gears 23 and 35 are rotated in opposite directions about the common axis 26^b, and such axis is shifted in the manner necessary to maintain the pitch surface of the master internal gear tangent to the pitch surface of the driving pinion. The reaction of the gear 35 on the driving pinion and the inter-reactions between the external and internal master gears and the intermediate pinions combine so to shift the work holder as to maintain between the gear blank 17 and the cutter 14 exactly the same condition of rolling tangent

pitch contact which obtains between the master internal gear and the driving pinion. In this way teeth are cut in the work on a pitch line which conforms exactly in its irregularities to the pitch line of the master internal gear.

The shape and pitch of the teeth cut in the work may be made identical in form, dimensions, and pitch with the teeth of the master gear by using a cutter 14 of which the tooth-like projections are designed according to well understood principles to generate such teeth, but the invention is not limited to a means for securing such exact identity of the work to the master gear, for it is part of my contemplation to generate teeth of other forms and pitch in the work from the teeth of the master gear. These characteristics of the teeth cut in the work are governed entirely by the corresponding characteristics of the cutter. What I have accomplished by the present invention is to produce exact correspondence between the pitch line of the teeth cut in the work and the pitch line of the teeth in the master gear.

An external gear having a pitch line or surface conforming exactly to the pitch surface of the combined gear and former 35 is produced by the same means in substantially the same way, as shown in Fig. 2. A gear blank 38 is mounted upon the holder 18^a and is alined with the combined external gear and former 35 by means of a stud 39 passing from the axis of the gear 35 and 103 clamped thereto by a nut 39^a, and upon which the blank 38 is clamped by a nut 38^a. This stud is free to rotate within its bearing in the holder 18^a. The holder and the gear blank are then given translative movements 105 with relation to the cutter which correspond to the irregularities of the external master gear 35 instead of to those of the internal gear. The same pinion 26 serves in this case also as the driver, the entire collection 110 of gears and pinions being then placed at the opposite side of the axis of the spindle so that the acting portion of the cutter will be at the forward side of the cutter spindle, as before.

In the foregoing description I have described the formers as being identical with the pitch lines of the gears wherewith they are respectively associated; but I do not limit the invention to an apparatus in which this relation occurs, since the same results may be secured if the formers are similar in outline to the respective pitch lines. By the term "similar" in this connection I mean the condition in which the surface of the former is projected beyond or withdrawn within the pitch line of the gear with which it is associated in such a manner that the normal distance between corresponding points in the former outline and the pitch 130

line is uniform throughout the entire circuit of the gear. Such a condition is shown in Fig. 4 where essentially the same arrangement of elements is shown as in Fig. 3, with this difference that the former surface 25^a of the internal gear 23^a, and the former surface 37^a of the external gear 35^a are withdrawn or retracted from the pitch lines of these gears, while the former surface 28^a of the driving pinion 26^a, and the former surfaces of the other pinions are extended beyond the pitch lines of such pinions. The distance by which the formers of the master gears are so withdrawn is equal to that by 15 which the former elements of the pinions are projected, whereby the distances between the centers or axes of the intermeshing gears or pinions remain the same as though the formers were in exact alinement or identity 20 with the respective pitch lines. In either case, whether the former is identical with the pitch line of the gear or is similar to it, there is a correspondence in outline between the former and the gear, wherefore the term 25 "correspond", or "corresponding", used in the following claims, is intended to embrace both the condition of identity shown in Fig. 3 and that of similarity shown in Fig. 4, between the formers and the gear pitch 30 lines.

The present invention is not limited to a work holding device in which the master gear is retained in mesh with the driving pinion by such a collection of floating gears 35 and pinions as has been hereinbefore described. The same results, in so far as concerns positively retaining the master gear in mesh with the driving pinion are secured by the means illustrated in Figs. 5 and 6, 40 designed for cutting external gears, and in Figs. 7 and 8 arranged for cutting internal gears. And first as to Figs. 5 and 6; the same reference characters are used in these figures to designate parts corresponding to 45 those which are shown in Fig. 2. In the construction now being described I provide a cam or former 49 which is secured to the master gear 35 by means of screws 41. The periphery of the former 40 bears against 50 the periphery of a roll 42 which is mounted to turn about a stud 43 which is fixed in the table 10 and is made steady at its upper end by a bearing plate 44 fixed to an upstanding lip 45 on the table. The gear 35 has a former surface or portion 37, coinciding with the pitch line of the gear, like the former shown in Fig. 2, which bears against the former portion 28 of the driving pinion 26. The outline of the former 40 is similar 55 to that of the former 37, and it is secured with its major axis at right angles to the major axis of the former 37, as appears from Fig. 6. The relation between these two formers is therefore such that the distance from any point, as α , (Fig. 6) in the

surface of the former 40 to the projection in the plane of said former of the point b in the former 37 (that is, the pitch line of the master gear) diametrically opposite through the axis of the master gear, is equal to the 70 distance from any other point c in the surface of former 40 to the projection in the same plane of the diametrically opposite point d in the surface of the former 37 and pitch line of the master gear. Consequently, 75 as the driving pinion and the abutment roll 40 are at an invariable distance apart, the effect of these two formers is to cause such shifting of the work holder bodily as will maintain the former surfaces 37 and 28 in 80 tangent contact; the former 40 acting to bring points in the receding parts of the former 37 up to the former 28. The master gear 35 and the former 40 are keyed by means of a key 46 to a tubular hub portion 85 47 on the work holder 18^b, on which the stud 39^a carrying the work piece (gear blank) 38 is held against rotation by a key 48. The former 40 has a second surface 49 which is concentric with the axis of the 90 stud 39^a, that is, the common axis of the former 40 and the master gear, and the table carries fixed abutments 50 on opposite sides of the surface 49 and in tangent contact therewith to guide the work holder and 95 prevent its shifting to either side of the line between the centers of the driving pinion and of the abutment roll 42.

In Figs. 7 and 8 the same principle is applied for cutting an internal gear, with this 100 modification that the roll 42^a, which corresponds to the roll 42, bears against an external cam surface 51 on the master internal gear 23^a, such surface being similar at all points to the pitch line of the teeth of said 105 master gear and to the former surface 25 thereof.

It will be evident that each of the modifications last described, (Figs. 5-8) as well as in each form of the invention first described, the master gear and work holder are moved to carry that part of the work piece which is adjacent to the cutting point, toward the cutter when receding points in the pitch line of the work approach the cutting position, by the reaction of a cam surface or former in rigid connection with the work holder against an abutment, and to carry the same away, when advancing points in said pitch line approach the same 115 position, by the reaction of the same, or a similar cam or former against a former connected with the driving pinion. In the case first described (Figs. 1-4) the abutment comprises the irregular gear, other than the 120 one to which the work piece is secured, and the floating pinions, these being a floating abutment; while in the last described case the abutment is fixed as to its location. In 125 both cases the results accomplished are the 130

same, namely, to shift the gear blank with respect to the cutter translatively so that its axis is progressively advanced toward and withdrawn from the axis of the cutter 5 in such manner that points in the gear blank in axial alinement with successive points in the pitch line of the master gear are brought successively tangent to the pitch line of the cutter at a point in axial alinement with the 10 pitch line tangent point between the master gear and master pinion. Said abutments are in all cases positive in their action, but have rolling contact with the reacting surfaces, whereby the desired result is accomplished with the maximum of accuracy and 15 the minimum of frictional resistance.

The foregoing description and the drawings relating thereto illustrate the two cases of cutting gears, that is, the internal and 20 the external gear. Gears of any form or character of irregularity may be cut by the means herein described, since whatever their form may be, the work carried out will have irregularities conforming exactly to those 25 of the master gear.

The term "irregular" used in this specification and in the following claims, has a special meaning as applied to a gear, meaning any form of gear wherof the line of 30 teeth is otherwise than concentric with the axis about which either the gear is designed to rotate, or a pinion in mesh with the gear is designed to revolve when traveling around the gear in a planetary manner.

35 Although I have shown and described the part 18, and correspondingly 18^a and 18^b, as a work holder, I wish to point out that I do not limit the invention to an apparatus in which there is a work holder so-called 40 additional to the master gear. In effect the holder is simply a convenient means for connecting the gear blank or work piece to the master gear chosen as the model to which the work is to conform, and to all intents and purposes the work holder is a part 45 of such master gear. It may be correctly considered therefore that the master gear is the work holder itself, and the part 18 is the means which indirectly connects the work to 50 such master gear. The term "work holder" may be considered as embracing the master gear and to include an arrangement in which the work piece is directly mounted on such master gear without the interposition 55 of any intermediate holder, as well as the arrangement here shown in which such intermediate holder is employed.

What I claim and desire to secure by Letters Patent is:

60 1. A machine for generating and cutting irregular gears comprising a blank holder, a cutter having tooth-like projections, means for producing relative cutting movements between the cutter and the blank holder, a 65 means for shifting said blank holder, com-

prising a driving pinion having a former similar to its pitch line, an integral gear and an external gear both meshing with said pinion and each having a former surface similar to the pitch line of its teeth 70 in tangent contact with the former of the driving pinion, the point of pitch line tangency between the driving pinion and one of said gears being in alinement in the direction of cutting with the pitch line tangent point of the cutter and gear blank, one of said gears being rigidly connected to the blank holder, and floating pinions interposed between the internal and external gears in mesh therewith and each having a 75 former surface tangent to the formers of both said gears.

2. In an apparatus for cutting irregular gears and in combination with a rotating and axially movable gear-shaped cutter, a 80 work driving spindle in approximate axial alinement with said cutter, a master pinion on said spindle arranged with a point in its pitch line in a line parallel with its axis passing through a point in the pitch line of 85 the cutter, and irregular master gears in mesh with said pinion, the work piece being rigidly connected with one of said master gears.

3. In a machine for generating and cutting teeth in irregular gears, a means for holding and moving a work piece, comprising a master gear to which the work piece is rigidly connected, a driving pinion in 90 mesh with said gear, and a second master gear also in mesh with the driving pinion, one of said master gears being an internal gear surrounding the other master gear and the driving pinion.

4. In a machine for generating and cutting teeth in irregular gears, a means for holding and moving a work piece, comprising a master gear to which the work piece is rigidly connected, a driving pinion in 95 mesh with said gear, a second master gear 100 also in mesh with the driving pinion, one of said master gears being an internal gear surrounding the other master gear and the driving pinion, and a table on which said gears are supported with freedom to move 110 both rotatively and translatively.

5. In a gear cutting apparatus, the combination with a rotatory and axially reciprocating gear-shaped planing cutter, of a supporting table, a master gear having an 115 irregular pitch line, with which the work piece is connected, a spindle in approximate alinement with the cutter, a driving pinion on said spindle in mesh with said gear, the gear being free to move upon the table, and a collection of gears and pinions in floating 120 mesh with said driving pinion, with said master gear, and with one another, arranged to constrain movements of the master gear to traverse past the driving pinion in pitch 125 130

line tangent rolling contact therewith, whereby the work piece is given a similar movement with respect to the cutter.

6. A work holding and shifting means for a gear cutting machine, comprising a support, an internal master gear, an external master gear within the space surrounded by the internal gear, and a number of pinions spaced about the external gear between the latter and the internal gear and in mesh with both, a driving spindle connected with one of said pinions, the other pinions and gears resting on said support and being free to move over the surface thereof, and means for attaching a gear blank to one of said master gears.

7. In a gear cutting machine having a cutter, a means for supporting and so moving a gear blank as to cause the cutter to produce an irregular line of teeth in such blank, comprising an irregular master gear to which the blank is connected, a support on which said master gear is adapted to move, a driving pinion in mesh with said master gear located with the tangent point of its pitch line contact with the gear in the path of travel of the acting part of the cutter, a second master gear meshing with the driving pinion, and pinions interposed between the teeth of said gears, the said gears and pinions being arranged to cause successive points in the pitch line of the first master gear to pass across such path of travel, whereby the teeth produced in the blank are cut on a pitch line conforming to that of the master gear.

8. In a gear cutting machine having a cutter, a means for supporting and so moving a gear blank as to cause the cutter to produce an irregular line of teeth in such blank, comprising an irregular master gear to which the blank is connected, a support on which said master gear is adapted to move, a driving pinion in mesh with said master gear located with the tangent point of its pitch line contact with the gear in the path of the acting part of the cutter, a second master gear meshing with the driving pinion, at the opposite side thereof from the point of contact between the pinion and the first master gear, said gears occupying the same plane and having approximately the same axis, and a plurality of pinions disposed in planetary relation to said axis and in mesh with both gears, whereby to maintain the said tangent point, as the driving pinion and the first master gear rotate, in said path.

9. A gear blank holding and driving means for a gear cutting machine comprising an irregular master gear to which the gear blank is adapted to be connected, a driving pinion in mesh with said master gear, a second master gear in mesh with said pinion on the opposite side of the axis

from the point thereof in mesh with the first master gear, said gears and pinion being in the same plane, and a number of planetary pinions in mesh with both gears.

10. A gear blank holding and driving means for a gear cutting machine comprising an irregular master gear to which the gear blank is adapted to be connected, a driving pinion in mesh with said master gear, a second master gear in mesh with said pinion on the opposite side of the axis from the point thereof in mesh with the first master gear, said gears and pinion being in the same plane, and a number of planetary pinions in mesh with both gears, said gears and pinions all having former portions or surfaces corresponding to the pitch lines of their teeth arranged tangent one to another.

11. A gear blank holding and driving means for a gear cutting machine comprising an irregular master gear to which the gear blank is adapted to be connected, a driving pinion in mesh with said master gear, a second master gear in mesh with said pinion on the opposite side of the axis from the point thereof in mesh with the first master gear, said gears and pinion being in the same plane, and a number of planetary pinions in mesh with both gears, each of said pinions and gears having a smooth former surface similar to the pitch line of its teeth and being tangent to the former surfaces of the gears and pinions with which it meshes.

12. A gear blank holding and driving means for a gear cutting machine comprising an irregular master gear to which the gear blank is adapted to be connected, a driving pinion in mesh with said master gear, a second master gear in mesh with said pinion on the opposite side of the axis from the point thereof in mesh with the first master gear, said gears and pinion being in the same plane, and a number of planetary pinions in mesh with both gears, each of said pinions and gears having a smooth former surface similar in outline to the pitch line of its teeth and in tangent contact with the former surfaces of the other gears and pinions with which its teeth are respectively in mesh.

13. In a machine for generating and cutting the teeth of irregular gears, in combination with a cutter having cutting projections of which the outlines at their cutting edges correspond to the outlines of gear teeth and are arranged on a pitch line transverse to the direction of cutting, a master gear having teeth in an irregular pitch line and being adapted to have a gear blank connected to it, a driving pinion meshing with said master gear for giving the generating movement to the gear blank, the element in the pitch surface of said pinion which is tangent to the pitch surface of the master gear being alined with the point on the

- pitch line of the cutter which comes tangent to the pitch line of the gear blank, and a positive means for shifting the master gear toward the pinion as points in receding portions of the pitch line thereof approach the tangent position, said means being constructed to permit recession of the master gear when points in its pitch line approach such tangent position.
- 10 14. In a machine for cutting irregular gears, a shiftable gear blank holder including a master gear having teeth arranged in an irregular pitch line, a driving pinion turning about a fixed axis and meshing with said master gear for giving the generating movement thereto and to the work and complementary cam means and abutment means arranged to act positively in so shifting the master gear as to retain it in mesh with the driving pinion when the receding portions of the pitch line thereof approach the pinon.
- 15 15. In a machine for generating and cutting irregular gears, a blank carrying master gear having teeth in an irregular outline, a driving pinion meshing with said master gear, a cam element associated with said master gear, and an abutment in rolling contact with said cam element adapted to exert pressure positively thereon for maintaining the master gear in mesh with the pinion.
- 20 16. A work holding means for a gear cutting machine comprising a master gear having teeth in a pitch line which is irregular corresponding to the irregularities of the gear to be cut, a driving pinion meshing with said gear, an abutment, and a cam or former having an irregular outline associated with said gear and bearing upon said abutment, the abutment being formed and arranged to maintain the gear in mesh with the pinion.
- 25 17. A holder for a gear cutting machine adapted to present an irregular gear blank in position for cutting, comprising an irregular master gear, a table or support on which said master gear is mounted in position for shifting thereover, a driving pinion meshing with said master gear, a cam or former associated with said gear having an outline corresponding to the pitch line of the gear, and an abutment bearing against said cam, the abutment being so arranged and the cam so designed as to cause and permit the gear to shift over said table as successive points on the pitch line of the gear come tangent to the pitch line of the pinion.
- 30 18. In a work holding means for a gear cutting machine, an irregular master gear having a pitch line corresponding to that of the gear to be cut, and adapted to be rigidly connected with a gear blank, a driving pinion meshing with said irregular gear, and positive means for maintaining the pitch line of the gear in constant rolling contact with the pitch line of the pinion.
- 35 19. In a gear cutting machine, a means for supporting and giving generating movements to an irregular gear blank, comprising a master gear having an irregular pitch line with which the gear blank is connected and having an integral cam or former element of which the outline corresponds to its pitch line, a driving pinion meshing with said gear and having an integral former or cam portion corresponding in outline to its pitch line and in tangent contact with said portion of said master gear, and means for maintaining the said formers in contact with one another.
- 40 20. In a gear cutting machine, a means for supporting and giving generating movements to an irregular gear blank, comprising a master gear having an irregular pitch line with which the gear blank is connected, and a pinion meshing with said master gear, said master gear and pinion carrying cam elements in contact with one another and being similar in outline respectively to the pitch line of the gear and the pitch line of the pinion, and being so related to such pitch lines respectively as to limit the interpenetration of the teeth of said gear and pinion to pitch line tangency.
- 45 21. In a gear cutting machine, a means for supporting and giving generating movements to an irregular gear blank, comprising a master gear having an irregular pitch line with which the gear blank is connected, a former associated with said master gear having its periphery similar to the pitch line of the gear but projected beyond the same at all points, and the driving pinion having an associated former of which the periphery is similar in outline to the pitch line of the pinion but retracted at all points within such pitch line a distance equal to the projection of the first named former beyond the pitch line of the master gear.

In testimony whereof I have affixed my signature.
